MOISTURE BOX

Louis P. de Give, Atlanta, Ga.

Application August 26, 1939, Serial No. 292,099

4 Claims. (Cl. 236—44)

The invention is a cabinet for curing or seasoning materials under prescribed constant conditions of surrounding atmosphere, especially materials which require a high degree of constancy of both temperature and humidity, as for example, the test samples incident to the manufacture of hydraulic cements and the like, the proper treatment of which does not tolerate any substantial variation from a constant condition.

10 By the apparatus constituting this invention the atmosphere within a curing cabinet is automatically kept substantially constant as to both temperature and relative humidity over long periods and notwithstanding that the materials or samples themselves may be undergoing chemical changes involving the transfer of both heat and moisture. Heretofore the automatic control of such cabinet has been considered exceptionally good if the temperature variation was as little

20 as 3° F., with corresponding changes in relative humidity, but by the system herein disclosed the variation is confined to less than one-half degree and is normally not over 0.4° F., with a corresponding constancy of the relative humidity.

25 The drawing shows the preferred form of the invention, Fig. 1 being a vertical section, Fig. 2 a cross section on line II—II and Fig. 3 a section on line III—III of Fig. 1, and Fig. 4 a section of the heater units.

30 The cabinet proper, marked 1, is provided with a central vertical partition 2 and a series of interior shelves 3 of wire-mesh, or other type suited to support the material or test-pieces without too much obstruction to air circulation. Access is afforded to the shelves by suitable hinged doors which appear in Fig. 2 and are normally closed. The cabinet and its doors may be of any suitable construction preferably heat insulated throughout, although perfect insulation is not required.

40 To the bottom of the cabinet proper there is attached a supplementary uninsulated metal chamber 4 in communication with the shelf chamber through the openings 5 and 6 at either side, thus providing for an air circulation which descends through the opening 5, flows thence laterally through the passage 7 and thence upwardly through opening 6. A fan 8 belt-driven by an electric motor 9 and located in the passage 7 maintains the air circulation at a constant rate.

45 One side of the lower chamber is made deep and wide to hold a relatively large body of water, kept at constant level by a ball float valve 10, and a metal cover 4a is provided over this part of the chamber to separate the water surface from

5 some heat exchange from one to the other. The rest of the lower chamber is constituted of a shallower and narrower passage 7 in which the fan 8 is located and through which the fan draws the air from the wider part thus giving it maximum velocity at this point. All of the internal surfaces of the two chambers are appropriately sloped to drain any condensed moisture toward the water reservoir in the lower chamber.

10 An electric heater unit 11 is mounted in the lower chamber side wall in a horizontal position directly over and close to the water surface and on this element is hung a wide belt of wicking 12, the lower part of which hangs through a narrow slot in the cover 4a and dips in the water. 15 This heater is of elongated form so as to accommodate a wide wick and is formed of an electric resistance coil 13 housed within a very thin walled tube (Fig. 4) with no thick metallic parts within the chamber such as would serve as reservoirs 20 of heat, and consequently it heats and cools almost instantaneously or without lag. The head or base of this heater, which necessarily contains more metal than the coil and tube, is preferably mounted on the exterior of the chamber wall 25 and insulated from it as indicated in Fig. 2.

25 As shown by the diagram, the current to the motor is branched to the heater unit 11, just described, through a hygrostat switch 14, mounted on the side wall of the cabinet in the ascending 30 side of the air circulation, and the heater 11 is therefore rendered active or inactive on the call of this hygrostat. The latter may be of the mercurial or bimetallic type but is of high sensibility and adapted to control its circuit on a fractional 35 degree change and it is adjustable to work on different selected temperatures. Such instruments are available on the market and do not require description. Its bulb element is covered with a wick that is kept saturated by dipping 40 into a water cup 15.

Supplementing the above control there is also mounted in the ascending air current a dry bulb thermostat 16 connected in another branch of the motor circuit in series with a second electric 45 heater unit 17, constituted of a naked resistance coil and located in the passage 7 directly in front of the circulation fan and therefore at the point of highest velocity in the circulation.

This thermostat 16 is also of the high sensibility type and will be understood to call the heater 17 into and out of action according to minute variations of the (dry bulb) temperature of the ascending air.

50 For observation purposes two other thermal 55

indicators 18 and 19, either direct or recording, are provided in the cabinet side wall 19 with their bulb elements on the inside of the cabinet and their scales visible on the outside. One of them, 18, has its bulb kept wetted by means of a wick dipping into a water cup 20 and the bulb of the other is naked, but both are subject to the same air flow.

The operation is as follows: Assuming, for example, that it is required to maintain a constant relative humidity of, say, 96.4% at a constant temperature of 70° F., the hygrostat 14 and the thermostat 16 are set accordingly and the fan circuit is closed starting the circulation. If the initial conditions are less than the settings, one or both of the heater elements at once become active and continue so until the condition corresponding to the settings has been obtained. The heating of the broad band of wicking 12 generates water-vapor which is taken up by the air current and further heated by its passage over the heater 16, thereby increasing the temperature and adding moisture. Thereafter variation of either factor of the condition will call one or the other heater units into or out of action, it being noted that the effect of heater 11 is to supply heat plus vapor while the heater 17 supplies heat alone and further that the relatively large volume of water in the tank 4 being closely related to the path of air flow functions to oppose or hold back excessive temperature changes, thus contributing to the uniformity of the condition.

I claim:

1. A seasoning cabinet comprising an upper shelf-containing chamber and a lower chamber with connecting passages between them to accommodate air circulation including both chambers, an air circulating fan in the lower chamber and a constant level water reservoir therein for holding a body of water adjacent to said air-flow, an elongated electric heater unit horizontally mounted above said body of water, covered with a wick dipping into the water, a second electric heater unit mounted in the air-flow, and a hygrostat and a thermostat in the

shelf chamber respectively connected to control the circuits of said heater units.

2. A seasoning cabinet comprising an upper shelf-containing chamber and a lower chamber in communication therewith to accommodate an air circulation including both chambers, said lower chamber having a deep part for holding water and a shallower part, said deep part having a wick-covered electric heater unit mounted over the water with said wick dipping into said water, said shallower part having an electric heater unit and a fan mounted therein, and hygrostatic and thermostatic control members mounted in the upper chamber and respectively controlling said wick-covered and other heater unit.

3. A seasoning cabinet comprising an upper shelf-containing insulated chamber and a lower chamber in communication therewith for together accommodating an air circulation, said lower chamber having a deep part for holding a body of water and a shallower and narrower part, an electric fan and an electric heater unit mounted in said narrower part and in the air circulation, a slotted cover over the said body of water adapted to separate the air flow therefrom, an elongated electric heater unit horizontally mounted over the cover and provided with a wick dipping in the water through the cover slot, and thermostatic and hygrostatic control members mounted in the shelf chamber, respectively controlling the circuits of said heater units.

4. A seasoning cabinet comprising an upper shelf-containing chamber and a lower chamber with connecting passages between them to accommodate air circulation including both chambers, an air circulating fan in the lower chamber and a water reservoir therein for holding a relatively large body of water in heat-exchanging relation to but out of contact with the air-flow, means for delivering vapor from said water to the air flow, an electric heater mounted in the air-flow, and a hygrostat and a thermostat in the shelf chamber respectively connected to control said means and heater.

LOUIS P. DE GIVE.
